[57] CLAIM

The ornamental design for an adaptable canopy cover for infant car seat or carrier, as shown and described.

DESCRIPTION

FIG. 1 is a front elevational view of the adaptable canopy cover for infant car seat or carrier showing our new design; FIG. 2 is a rear elevational view thereof; FIG. 3 is a right side view thereof; FIG. 4 is a left side view thereof; FIG. 5 is a top plan view thereof; FIG. 6 is a bottom plan view thereof; and, FIG. 7 is an isometric view thereof.

The broken lines shown in all views represent stitching. The schematic cross-hatching shown in FIGS. 3, 4, 6 and 7 is understood to represent fabric or netting and would be continuous throughout the implied areas.
